Primary Examiner — Stacia Cadmus(57) **CLAIM**

I claim the ornamental design for a right automotive wheel, as shown and described.

DESCRIPTION

FIG. 1 is a front view of the right automotive wheel of the claimed design;

FIG. 2 is a front perspective view of the right automotive wheel of FIG. 1;

FIG. 3 is another perspective view of the right automotive wheel of FIG. 1;

FIG. 4 is another perspective view of the right automotive wheel of FIG. 1;

FIG. 5 is another perspective view of the right automotive wheel of FIG. 1;

FIG. 6 is another perspective view of the right automotive wheel of FIG. 1; and,

FIG. 7 is a side view of the right automotive wheel of FIG. 1.
